DESIGN FOR AN ASH TRAY

Francis A. Peden, Brooklyn, N. Y.

Application September 8, 1945, Serial No. 121,953

Term of patent 7 years

(Cl. D85—2)

To all whom it may concern:

Be it known that I, Francis A. Peden, a citizen of the United States and resident of Brooklyn, in the county of Kings and State of New York, have invented a new, original, and ornamental Design for Ash Trays, of which the following is a specification, reference being had to the accompanying drawing, forming part thereof in which:

Fig. 1 is a perspective view of an ash tray, showing my new design;

Fig. 2 is a side view of the ash tray shown in Fig. 1; and

Fig. 3 is a rear end view of the ash tray shown in Figs. 1 and 2.

I claim:

The ornamental design for an ash tray, as shown.

FRANCIS A. PEDEN.
